Primary Examiner — Mary Ann Calabrese(74) *Attorney, Agent, or Firm* — Venable LLP; Steven J. Schwarz; Elizabeth C. Gitlin(57) **CLAIM**

The ornamental design for a desk, as shown and described.

DESCRIPTION

FIG. 1 is a front-right perspective view of the desk according to the claimed design shown in a lowered position;

FIG. 2 is a front view of the desk of FIG. 1;

FIG. 3 is a rear view of the desk of FIG. 1;

FIG. 4 is a left side view of the desk of FIG. 1;

FIG. 5 is a right side view of the desk of FIG. 1;

FIG. 6 is a top view of the desk of FIG. 1; and,

FIG. 7 is a front-right perspective view of the desk of FIG. 1 shown in a raised position.

The features shown in broken lines represent portions of the desk which form no part of the claimed design. The bottom of the desk is substantially flat and unornamented.
